UNITED STATES PATENT OFFICE.

VOLUSIN BUDE, OF EAST SAGINAW, MICHIGAN.

AIR-HEATING FURNACE.

SPECIFICATION forming part of Letters Patent No. 258,017, dated May 16, 1882.

Application filed April 25, 1881. (No model.)

To all whom it may concern:

Be it known that I, VOLUSIN BUDE, a citizen of the United States, residing at East Saginaw, in the county of Saginaw and State of Michigan, have invented a new and Improved Air-Heating Furnace, of which the following is a specification.

My invention relates to an air-heating furnace which is provided with a central annular grate and fire-chamber inclosing a central air-duct, and also with a series of concentric radiating walls, forming a series of concentric air-ducts surrounding the fire-chamber.

My invention further relates to the mixture of volumes of air heated to a high temperature by contact with a series of radiating-surfaces with a volume of air heated to a less degree by similar radiation, and to the apparatus whereby this result is attained.

My invention further relates to the storage and moistening of bodies of air heated as above mentioned.

My invention further relates to the formation of smoke-tight joints, whereby the contamination of the pure heated air, due to the escape of smoke and gas from the fire-chambers and connecting flues, is prevented; also, to certain details of construction, as herein-after set forth.

To the above ends my invention consists of a furnace having a central air-duct formed by the interior walls of the surrounding ash-pit and fire-chamber. This passage contracts in area for about half its vertical height, at which point it begins to expand in area vertically to its top. By this means the ascending current of air is at first compressed, which aids materially in its thorough heating, and then said air is allowed to expand in the remainder of its ascent. Surrounding this central air-duct is a circular fire-chamber, containing a correspondingly-shaped grate. The lower half of this chamber is formed of a gradually-increasing area from the bottom upward, at which point the area of said chamber gradually decreases to its top. By this arrangement a thorough consumption of the products of combustion is produced in the chamber above the fire. The air-duct surrounding and immediately contiguous to the exterior wall of the fire-chamber is similarly arranged, as to con-

tracting and expanding areas, to the interior air-duct, with this difference, that the outer wall of said duct is straight while its inner wall alone has the angular form described. 55 The external duct is of equal area throughout, its walls being perpendicular, as the volume of air therein is to be only slightly heated. Upon the upper part of the outer jacket of the furnace is a curved annular plate or deflector, 60 which causes the air rising in the outer duct to pass across the currents from the central and middle ducts, thus lowering the temperature of the mixed currents to a healthful degree. An annular U-shaped trough is attached 65 above the deflector to the inner side of the jacket. This trough is constantly supplied from without the furnace, and the vapor arising from said trough, due to the high temperature within the furnace, is absorbed by the air 70 which is thus impregnated with moisture.

In order that my invention may be more thoroughly understood, I will proceed to describe its construction, with reference to the accompanying drawings, in which—

Figure 1 is an elevation, partly in section, of the furnace and its foundation-walls. Fig. 2 is a plan view of the lower part of the furnace on the line h h of Fig. 1, showing the base-plate and its relative position. Fig. 3 is a plan view, 75 partly in section, one half being on the line h' h' and the other half on the line h'' h'' of Fig. 1. Fig. 4 is a vertical section of the fire-chamber head, one of the conical connecting-pipes, with its connections, and the central stack. 80 Fig. 5 is a detached view of the shaker-wheel and a portion of the grate. Fig. 6 is a detached view, in vertical section, of a portion of the outer wall of the fire-chamber, showing its smoke-tight joint. Fig. 7 is a detached view, 85 in vertical section, of a portion of the inner wall of the fire-chamber, showing its smoke-tight joint. Fig. 8 is a detached view, partly in horizontal section, of the fire-pot, showing its formation. Fig. 9 is a plan view of a portion of 90 the annular perforated brace-plate.

The furnace is built over a central horizontal air-duct formed by the wall d and upper and lower courses, a c , all of which are placed in the earth, as shown at e . Within the air-duct thus formed are placed a suitable number of piers or supports, d , resting at their

lower ends on the layer *c* of masonry and at their upper ends supporting the base-plate *A*, which also rests upon the top of wall *d*. This plate is annular in form, (constructed either of one piece or in sections,) and is provided with 5 openings *A'* for the admission of air to the central and surrounding vertical ducts of the furnace. It also forms the closed bottom or floor of the ash-pit *C*. The outer and inner walls, 10 *B*, *B'* *B*, form the supports for the grate *F*, and also for the walls of the fire-chamber. Above the ash-pit *C* is the grate *F*, which is of annular form, and is composed of a number of sections of such size as to be removed through 15 the furnace-doors. This grate rests at its inner portion on top of the wall *B* of the ash-pit and at its outer portion on a supporting-ring, *E*, which in turn rests on the wall *B'* of said ash-pit, the body of said grate being formed of 20 a series of radial bars, with elongated openings between them. In the ash-pit, just below the grate *F*, is a toothed shaker-wheel, *k*, which is mounted upon a horizontal shaft journaled in the walls of the pit, its outer portion passing through a sleeve, *Y*, on the outer 25 jacket of the furnace, and terminating at its outer end in a square head adapted to enter the eye of a crank-arm. The teeth of this wheel *k* mesh into the open spaces between 30 the grate-bars, so that by rotating the wheel the grate is caused to turn on its supports. Two or more openings communicating with the ash-pit may be made in the walls of the furnace, said openings being provided with 35 hinged doors *D*, with draft-openings therein in customary manner.

The central air-duct, *W''*, of the furnace is formed by the lower and upper conical sections, *H* *H'*. The lower section, *H*, rests upon a 40 shoulder or rabbet in the upper end of the grate-supporter *B*, and extends obliquely upward, inclining inward, to its point of juncture with the section *H'*. The said section *H'* rests upon and overlaps the top of section *H*, and 45 extends obliquely upward with an opposite inclination to that of the lower section, *H*. The lap-joint of the sections *H* and *H'* is made tight by a ring, *J*, which embraces the outside of section *H'* and binds the meeting edges of 50 the two sections closely together. The sections *H* *H'* also form the inner wall of the combustion-chamber, the outer wall of which is formed by the lower and upper sections, *H''* *H'''*. The lower section rests upon a rabbet 55 in the supporting-ring *E*, and extends obliquely upward, with an outward inclination, to its point of juncture with the upper section, *H'''*. The upper section, *H'''*, rests upon and overlaps the top of lower section, *H''*, and extends 60 obliquely upward, with an inward inclination, the opposite of that of the lower section, *H''*. The lap-joint of these two sections is made tight by a ring, *I'*, which embraces the outside of section *H'''*, and binds the meeting edges 65 of the two sections closely together. The lower section, *H''*, is composed of a suitable number

of T-shaped sections, *m m*, with tongue-and-groove joints, bound together by a ring, *I*, embracing their outer ends. This construction is shown in Fig. 8, and while it is especially 70 applicable to the furnace herein described, it is also applicable to the fire-pots of stoves and furnaces generally. I propose to file a separate application for Letters Patent for this construction in its general application to stoves 75 and furnaces, and I hereby reserve to myself this right. At their upper ends the two upper sections, *H' H'''*, support an annular radiator-head, *K*, the two flanges of which embrace the ends of said sections between them. The 80 outer flange of the head *K* is of equal thickness throughout, and is set upon the body of the head, obliquely to correspond with the oblique position of section *H'''*, while the inner flange is of greatest thickness at a point midway between its point of juncture with the body of the head and its lower edge, making it triangular in cross-section, as seen in Fig. 4. A guard-plate, *M*, having openings or holes *p* for the passage of smoke, &c., is introduced 85 at the open side of the head *K*, and when pressed up into position its edges come in contact with the sides of the sections *H' H'''*, forcing them outward and making a tight joint between their opposite faces and the inner 90 faces of the flanges of head *K*. Said plate is secured in position, and its pressure on sections *H' H'''* maintained by screw-bolts *r*, passed through openings in the head *K*, and through similar openings or eyes, *r'*, in said plate, to the 95 lower screw-threaded ends of which nuts are attached and screwed up tight against the lower face of plate *M*.

The radiator-head *K* is formed with openings, surrounded by collars *L*, eight or more in 100 number, over which fit the lower ends of conical pipes *N*, of which there are a corresponding number, and these pipes, extending obliquely upward, are received at their upper ends by collars *Q* on the bottom of the stack *O*, said collars passing over the ends of pipes *N*. This stack *O* has an annular flange, *R*, upon its outer side to which the top *X* of the furnace is riveted, a tight joint being formed by a ring or washer, *R'*, placed above the top *X*. 105

Surrounding the outer wall of the fire-chamber is the middle radiating-wall, *T*, a space being left between the two, forming an air-duct, *W*. This wall *T* is a plumb vertical wall and extends up to a level with the lower edge of the deflector-plate *U* on the outer jacket of the furnace. Surrounding this wall *T* is the jacket *T'*, sufficient space being left between them to form the air-duct *W*. This jacket extends vertically upward to the top *X*, to the outer edge 120 of which it is riveted, said edge being turned down upon the outside of the jacket.

At a point level with the top of the middle wall, *T*, and upon the inner side of the jacket *T'*, is a deflector, *V*. This deflector is concave 125 on its lower face and convex on its upper face, the line of curvature being transverse of its

length. It extends entirely around the inside of the furnace-jacket and projects inwardly therefrom a distance about equal to the width of the air-duct W. Upon the upper side of the deflector U, and resting in the angle formed at its point of contact with the jacket, is the vaporizer V, which is a U-shaped trough, of cast-iron, extending entirely around the inside of the furnace. It is kept constantly supplied 10 with water, and the vapor therefrom is absorbed by the heated air in the chamber above the deflector.

The top of the furnace is provided with collars Z, surrounding openings in said top, and 15 adapted to receive hot-air pipes ramifying throughout the building. These collars Z may open from the sides of the furnace in cases where the roof is not enough higher than the furnace to admit of their being placed as shown.

20 Suitable doors, S S' and D D', of which there may be any suitable number, will of course be provided, suitable openings being made in the jacket and radiating-surfaces for their accommodation, and jambs n i i' will be attached to the jacket and walls in the customary manner.

Having thus described my invention, what I claim as new, and desire to secure by Letters Patent, is—

1. In an air-heating furnace, the annular fire-chamber G, constructed as described, in combination with the base-plate A, provided with openings A', and resting on the supporting-piers b and wall d, the central air-passage, W'', formed by the oppositely-inclined walls H H', 30 the air-passage W', formed by the oppositely-inclined sections H'' H''' and vertical annular wall T, and the air-passage W formed by the annular vertical wall T and jacket T', said jacket being provided with the deflector U and trough

V, substantially as and for the purposes set forth.

2. In an air-heating furnace, the annular fire-chamber G, formed of the outwardly-inclined sections H H'', resting upon the annular supporting-walls B B', with the interposed ring E, 45 the upwardly-inclined sections H' H'', provided with rings I' J, and united at their upper ends by radiator-head K and annular plate M, said plate being provided with openings p and holes r', and the bolts r, substantially as and for the 50 purposes set forth.

3. In an air-heating furnace, the annular fire-chamber G, constructed as described, and provided with the plate M and radiator-head K, having collars L, in combination with the conical pipes N, the stack O, provided with collars Q, annular flange R, and flange ring or washer R', the furnace-top X, and jacket T', substantially as set forth.

4. In an air-heating furnace, the combination 60 of the sections H H' H'' H''' with the rings I J, substantially as described.

5. In an air-heating furnace, the sections H' H''', in combination with radiator-head K, having collars L, plate M, provided with openings p and holes r', and bolts r, substantially as 65 set forth.

6. In an air-heating furnace, the grate F, composed of a series of radial bars with radial openings between said bars, the ring E and wall B B', in combination with the shaker-wheel k, shaft l, and wall T T', the latter wall, T', being provided with the sleeve Y, substantially as specified.

VOLUSIN BUDE.
